UNITED STATES PATENT OFFICE.

WILLIAM LOCKWOOD, OF MADRID, NEW YORK.

BUCKBOARD-WAGON.

SPECIFICATION forming part of Letters Patent No. 294,891, dated March 11, 1884.

Application filed September 8, 1883. (No model.)

To all whom it may concern:

Be it known that I, WILLIAM LOCKWOOD, of Madrid, in the county of St. Lawrence and State of New York, have invented a new and 5 Improved Buckboard-Wagon, of which the following is a full, clear, and exact description.

The object of my invention is to provide a simple arrangement of the springs and spring-braces for the buckboard which will be durable and inexpensive and give to the wagon all the easy-riding qualities of more expensive vehicles, while retaining all the lightness and ease of draft of the common buckboard.

The invention consists of the detailed construction and combination of parts, essentially as hereinafter fully described and claimed.

Reference is to be had to the accompanying drawings, forming a part of this specification, in which similar letters of reference indicate corresponding parts in all the figures.

Figure 1 is an under-side view of the improved buckboard-wagon, partly broken away and with the wheels removed. Fig. 2 is a side elevation of the buckboard of Fig. 1. Fig. 25 3 is a like view to Fig. 1, but showing a modified arrangement of the springs connecting the hind axle to the buckboard; and Fig. 4 is a longitudinal sectional elevation on the line $x-x$, Fig. 3.

30 The arrangement of the buckboard with the forward springs and front axle being the same in the construction shown in Figs. 1 and 2 as that shown in Figs. 3 and 4, the same description will apply to either, as follows:

35 a represents the buckboard, which may be made of any approved material and be of any desired size, and may or may not be fitted with a dash-board and one or more seats, as variously arranged in vehicles of this class.

40 b is a cross-bar, to which the three flat steel forward springs are connected by suitable bolts and clips, $c d$, as shown. These forward springs range fore and aft edgewise about in line with buckboard a , the two outer springs, e , connecting the buckboard at or near the side edges directly with the bolster f by clips f' , while the center spring, g , is bent downward beneath the front axle, h , with which and the bolster it connects by a bolt, i , which forms the 45 pivot or king-bolt, on which the forward running-gear of the vehicle may swing in turning.

Referring now to Figs. 1 and 2, j represents the rear cross-bar, fixed to the buckboard a . k is a center spring connected by suitable bolts and clips, $c' d'$, with the bar j and hind axle, 55 l . This spring k ranges in line edgewise with the board a , as do the three forward springs, $e e g$. The outer rear springs, m , are fixed suitably to bar j , and are set aslant or obliquely edgewise to the buckboard a , and connect by clips with the hind axle near to the shoulders of the wheel-hubs, so that while the elasticity of the springs m and spring k is available for easy up and down movement or 60 spring of the buckboard a , the oblique springs m act as braces to prevent any side sway or swing of the buckboard.

The arrangement of hind springs in Figs. 3 and 4 differs from that in Figs. 1 and 2 last above described only in that two fore and aft 70 central springs, o , connect the bar j near each edge of the buckboard with the hind axle, l , instead of the single central spring, k , and a spring bar or rod, p , connects the buckboard a at each side with the hind axle, l , instead of 75 the flat plate-springs m the vertical spring, the side-bracing actions being substantially the same in either case.

Any or all of the flat or plate springs used may consist of but a single plate, or be built 80 up of two or more leaves, to give the desired degree of elasticity, and easily carry the predetermined maximum load; and the springs may have any vertical curve to suit the desired height of the buckboard.

85 I am aware that it is not new to employ as a spring two bars so constructed as to converge at their middle portions, and to diverge at both ends, said convergent portions being connected to the buckboard, and the divergent 90 portions or ends connected to the front bolster and back axle; and in another instance to mount the body on a front and a rear frame-like spring intermediately, and at their inner ends connected to the body, while at the outer 95 ends one is connected to the head-block of the front axle, and the other to the rear axle.

Having thus described my invention, I claim as new and desire to secure by Letters Patent—

In a buckboard-wagon, the combination, 100 with the buckboard a and the front bolster, f , and axle h and the hind axle, l , of the cross-

pieces *b j*, secured to the buckboard a short distance inwardly from its ends, the central springs, *g k*, one secured to the under side of the front axle, *h*, and the cross-piece *b*, and the other to the same side of the hind axle, *l*, and the cross-piece *j*, the parallel side springs, *e e*, connected to the cross-pieces *b*, and above the front axle to the bolster *f*, and the rear oblique

bars or braces, *m m*, secured to the cross-piece *j* and hind axle, *l*, as shown and described, 10 and for the purpose set forth.

WILLIAM LOCKWOOD.
